(57) **CLAIM**

The ornamental design for an airless sprayer cartridge, as shown and described.

DESCRIPTION

FIG. 1 is a perspective view of an airless sprayer cartridge; FIG. 2 is a top plan view of an airless sprayer cartridge; FIG. 3 is a bottom plan view of an airless sprayer cartridge; FIG. 4 is a right side view of an airless sprayer cartridge; FIG. 5 is a left side view of an airless sprayer cartridge; FIG. 6 is a front elevational view of an airless sprayer cartridge; and,

FIG. 7 is a rear elevational view of an airless sprayer cartridge.

The broken lines in the Figures represent portions of an airless sprayer cartridge and form no part of the claimed design.
